HOSIERY MACHINE DRIVE

Chester W. Drake and William R. Harding, Pittsburgh, Pa., assignors to Westinghouse Electric & Manufacturing Company, East Pittsburgh, Pa., a corporation of Pennsylvania

Application November 12, 1937, Serial No. 174,201

14 Claims. (Cl. 66—82)

Our invention relates, generally, to variable speed machinery drives, and, more particularly to a system of speed control for full-fashioned hosiery knitting machines.

5 In the operation of full-fashioned hosiery machines, it is necessary that the machine be driven at different speeds for the several different steps in the knitting process. A very low speed, approximately 10 to 15 percent of the normal highest knitting speed, is necessary while the machine is being started and while the welt is being turned. During the forming of certain parts of the hose, a speed of approximately 80 percent of the highest knitting speed is necessary.

10 15 While the number of knitting stitches per course is being reduced to produce a narrowing of the hose, a speed of approximately 35 to 40 percent of maximum knitting speed is required. This is known as the narrowing process and the speed is reduced from normal running speed only 20 during the short interval necessary for reducing the number of stitches in the courses.

15 25 It is necessary that a high torque be maintained throughout the range of speeds of 10 percent to maximum and very considerable difficulty has been experienced in providing a drive system that will satisfy the desired speed and torque requirements.

20 30 An object of our invention is to provide a control system for an electric motor driven full-fashioned hosiery machine which shall function to provide a wide range of speeds while maintaining a high torque.

35 40 Another object of the invention is to provide a control system for an electrically driven full-fashioned hosiery machine which shall function to automatically govern the speed of the machine to provide the necessary speed for the several operations of the machine.

45 50 A further object of the invention is to provide a motor control system for an induction motor driven machine which shall function to provide a wide range of speeds for the machine while maintaining a desirable speed-torque characteristic at extremely low speeds.

55 These and other objects and advantages of the invention will be apparent from the following detailed description taken in connection with the accompanying drawings, in which

Figure 1 is a diagrammatic illustration of a preferred embodiment of the invention showing the cooperative relationship of the several elements of the control system.

Fig. 2 is a diagrammatic illustration of an

other embodiment of the invention in which additional automatic features are included.

Figs. 3 and 4 are charts showing the conditions of the relays and switching devices of the control systems of Figs. 1 and 2, respectively, for 5 producing the desired speeds, and

Fig. 5 is a chart showing the approximate speed-torque characteristics of a motor under control of the systems of Figs. 1 and 2.

In practicing the invention, we provide relay 10 means for varying the resistance in the rotor circuit of an induction motor to vary the motor speed within the higher speed ranges. Control of the motor to secure extremely low speeds is provided by varying the load on a generator 15 driven by the motor. The actuation of the relays is under manual control for certain of the speeds and automatic control for other speeds.

Referring to Fig. 1 of the drawings, a knitting machine is driven by a wound rotor induction motor 10 which is energized from the alternating current power source XYZ through the contact elements 12 of relay 1. The wound rotor circuit of the motor 10 has variable resistances 14 and 16, 18 and 20, 22 and 24 in its three branches 20 and connections are made through the contact elements 26 of relay 2 and 28 of relay 3 for shorting out various values of these resistances 25 so as to vary the resistance in the wound rotor circuit and in this manner vary the speed torque 30 characteristic of the motor 10.

A series excited generator 30 is connected to be driven by the motor 10 and a resistance 32 may be connected in series circuit relation with generator 30 through the contact element 34 of 35 relay 4. A circuit is arranged through contact element 36 of relay 5 for shorting out a part of the resistance 32 to vary the load on the generator 30.

When the rotor circuit is controlled by contact elements 26 of relay 2, the minimum of resistance is connected in the rotor of the motor 10 and the motor will have a speed torque characteristic which will be a curve which will lie between the curves A and B of Fig. 5, depending 40 upon the values of the resistance in the rotor circuit which, in turn, depend upon the position of the movable contacts on the variable resistors 14, 18 and 22. The speed of the knitting machine under these conditions at the torque required for operating the knitting machine would lie somewhere between the intersections of lines 45 A and B of Fig. 5 and the broken line ordinate which will represent knitting machine speeds of between 60 and 75 courses per minute. 50 55

- When only contact elements 28 of relay 3 are closed, such a resistance will be connected in the rotor circuit of motor 10 as will give it the speed torque characteristics which will lie between the curves B and C of Fig. 5, depending upon the amount of the resistance in the motor circuits, which is variable as stated hereinbefore, and this speed range will represent a knitting machine speed of between 40 and 60 courses per minute.
- With contact elements 26 and 28 in the open circuit position, and contact element 34 of relay 4 in the closed circuit position, the generator 30 and its connected resistance 32 will constitute such a load upon the motor 10 as to give it a net speed torque characteristic as is represented by the curve D of Fig. 5, the net torque in this instance being the torque required by the knitting machine itself, disregarding the torque required by the loaded generator 30. It will be seen that the knitting machine speed at its required torque will be approximately 30 courses per minute under these conditions.
- When it is necessary that the knitting machine be operated at a still lower speed, contact element 36 of relay 5 is closed to short out part of resistance 32 and thus increase the load on the generator 30. The net speed torque characteristic curve of the motor under these conditions is represented by the curve E of Fig. 5, and it will be seen that a knitting machine speed of approximately 8 courses per minute is produced under these conditions.
- Relay 1 is controlled by a circuit which extends from one conductor Y of the source of alternating current through conductor 38, conductor 40, control device 42 in its M1 position, conductor 44, the contacts of limit switch CC, conductors 46 and 48, the coil of relay 1 and conductors 50 and 52 to another conductor Z of the source of alternating current. After relay 1 has been energized, it will be seen that it closes its contact element 54 which completes a holding circuit for relay 1 through conductor 56 and the control device 42 when the control device is in positions M2 and M3.
- The relay 2 is controlled by a circuit which extends from the conductor Y of the source of alternating current through the conductors 38 and 40, contact element 54, conductor 56, control device 42 in the M3 position, conductor 58, contact element 60 of relay 5, conductor 62, the coil of relay 2, contact element 64 of relay 3, and the conductor 52 to the conductor Z of the source of alternating current.
- The control circuit of relay 3 extends from the conductor Y of the source of alternating current through conductor 38, to control device 42 either through conductor 40 or through conductor 40, contact element 54 and conductor 56, conductor 44, the contacts of limit switch CC, conductor 46, the contact elements of the limit switch N, conductor 66, the contact element 68 of relay 5, conductor 70, the coil of relay 3 and the conductor 52 to the conductor Z of the source of alternating current.
- The control circuit for relay 4 extends from the conductor Y of the source of alternating current through conductor 38, either conductor 40 or conductor 40, contact element 54 and conductor 56, the control device 42, the conductor 44, the contacts of limit switch CC, conductors 46, 48 and 72, the coil of relay 4, conductor 74, contact element 76 of relay 2, conductor 78, contact element 80 of relay 3 and conductor 52 to conductor Z of the source of alternating current.

A similar circuit is established through relay 5

between conductors 48 and 52 by conductor 82, the coil of relay 5, conductor 84, switch element 8C and conductor 86.

A control device 88 driven, as shown, in synchronism with the knitting machine is provided for actuating the limit switches N and CC after predetermined numbers of courses have been knitted. The control device 88 comprises a series of belt 90 and 92 upon which are mounted protuberances 94 in such positions and of such length as to hold the contacts of the limit switches N and CC in open circuit position for the desired intervals at the desired points in the process of knitting. The limit switch N is provided for producing the "narrowing" speed which is a speed of approximately 30 courses per minute, which is necessary in the knitting of the hose to permit reducing the number of stitches per course in the stocking. This speed is maintained for only very short intervals and it is, therefore, necessary that the protuberances 94 be very narrow so that limit switch N will be held in open circuit position for only a short time.

The contacts of the limit switch CC are connected to deenergize the relay 1 and, therefore, to deenergize the motor 10 at certain predetermined intervals in the knitting operation when certain machine adjustments must be made with the knitting machine idle.

Fig. 3 of the drawings shows the position of the various control switches and the several relays for producing the desired operating speeds of the knitting machine. In the usual cycle of operation for knitting full-fashioned hose, a speed of approximately 8 courses per minute is first produced to get the machine started. A knitting speed of from 60 to 75 courses per minute is then produced to knit the welt of the hose. While the welt is being turned, a speed of approximately 8 courses per minute is necessary. For normal knitting, the high speed of from 60 to 75 courses per minute is used. During the narrowing operation, a speed of approximately 30 courses per minute is employed and for certain parts of the knitting, it is necessary that a slow speed of from 40 to 60 courses per minute be provided. The chart of Fig. 3 illustrates which switches and relays are closed and energized to produce the various speeds necessary by the system of Fig. 1.

In the operation of the device of Fig. 1, the starting speed is produced by closing a push button switch 8C and moving control device 42 to the M1 position. It will be seen that this switching operation will cause relay 1 to energize the motor 10 through its contact elements 12, relay 5 will be operated to close its contact element 36 and relay 4 will be energized to close its contact element 34. The circuit of relay 2 will remain open, since its complete circuit depends upon the control device 42 being in the M3 position and the circuit of relay 3 will be opened by contact element 68 of relay 5. Thus, it will be seen that the motor 10 will have a net speed torque characteristic approximately as represented by the curve E of Fig. 5, and that the knitting machine will be operated at a speed of approximately 8 courses per minute.

When it is desired to run the knitting machine at high speed, control device 42 is moved to the M3 position and the push button switch 8C is moved to open circuit position. In this step of the operation of the system, it will be seen that relays 1, 2 and 3 will be energized and that contact elements 26 and 28 of relays 2 and 3, respectively, will be closed, producing the speed torque char-

acteristic represented by the range between the lines A and B of Fig. 5, or a speed of from 60 to 75 courses per minute depending upon the position of the movable contacts upon the variable resistors 14, 18 and 22. It will be seen that with relays 2 and 3 energized, contact elements 76 and 80 will be in the open circuit position to insure that the relay 4 be deenergized.

After the welt of the stocking is knitted and is ready to be turned, a speed of approximately 8 courses per minute is produced by closing the push button switch 8C with the control device 42 in the M3 position. This will produce the desired speed by energization of the relays described hereinbefore in connection with the starting speed of the knitting machine.

After the welt is turned, the normal high speed of from 60 to 75 courses per minute is again produced by moving the push button switch 8C to the open circuit position.

After knitting has progressed at the high knitting speed to where it is necessary to perform the narrowing action, the belt 90 will have moved to such a position as to cause one of the protuberances 24 to engage the limit switch N and open its contacts. It will be seen that this operation will cause relay 3 to be deenergized, which will close its contact element 80 and open its contact element 64. The opening of contact element 64 will cause the deenergization of relay 2 and its contact element 76 will close to complete a circuit through relay 4. With only relay 4 energized, all of the resistance 32 will be connected in circuit with the generator 38 and the knitting machine speed of approximately 30 courses per minute will be produced, since the motor 10 will then have the characteristic substantially as illustrated by curve D in Fig. 5.

For producing the slow knitting speed, of from 40 to 60 courses per minute, control device 42 is moved to the M2 position while relays 2 and 3 are energized, thus deenergizing relay 4 and leaving only the relay 3 energized. With only relay 3 energized, contact elements 28 will connect such a resistance in the rotor circuit of the motor 10 as to produce the speed torque characteristics represented by the range of characteristics between lines B and C in Fig. 5.

The operation of the limit switch CC is obvious from the drawings, since its contacts are connected in series circuit relation with relay 1 which controls the energization of the motor 10 through its contact elements 12. Should this limit switch operate while the control device 42 is in the M3 position, it will be seen that the machine will be shut down until the control device is again moved to the M1 position, since the stick circuit comprising contact element 54 and conductor 56 upon which the energization of relay 1 depends while the control device 42 is in the M3 position, is opened by the deenergization of relay 1 and the consequent movement of the contact element 54 to the open circuit position.

The modification of Fig. 2 is similar to that of Fig. 1, but has, in addition, automatic control for the slow knitting speed and the welt turning speed, so that these speeds are produced automatically at the desired time and are maintained for the desired length of time. Like reference characters denote similarly functioning elements in these two figures of the drawings, and it will be seen by reference to Fig. 2 that relay 1 is provided with a contact element 54 which closes

a holding circuit for relay 1 and contact elements 12 which connect the motor 10 to the alternating current source indicated by conductors X, Y and Z. In like manner, relay 2 which operates its contact elements 28 to connect a minimum of resistance in the motor circuit of motor 10 is connected in series circuit relation with contact element 68 of relay 5. In addition, a push button switch F is provided in series circuit relation with the coil of relay 2 to connect relay 10 2 in the circuit corresponding to the circuit through relay 2 controlled by the M3 position of controller 42 of Fig. 1. Relay 2 is also connected in series circuit relation with the normally closed limit switch SL which is operated by protuberances 84 on web 86 of the control device 88.

The circuit of relay 3, which operates its contact elements 28, to connect only a part of the resistances 16, 20, 24 in the rotor circuit of the motor 10 to produce the slow knitting speed is controlled by normally closed contact element 68 of relay 5 and normally closed contact element 88 of relay 2.

Relay 4 which closes its contact element 34 to connect the resistance 32 to place a load upon the generator 38 is controlled by the contact element 88 of relay 3.

The relay 5, which actuates its contact element 86 to increase the load on generator 38, is controlled by push button switch 8C, as described in connection with the device of Fig. 1, and this push button switch 8C is paralleled by normally open contact elements of limit switch W which are controlled by protuberances 84 on the web 100 of the control device 88 so that the welt turning speed may be produced automatically after the desired number of courses have been knit in the welt. It will be seen that the contact element 68 of relay 5 of the device of Fig. 2 serves the purpose of both contact elements 68 and 88 of the device of Fig. 1, since the contact 68 controls both relays 2 and 3 in the device of Fig. 2.

The chart of Fig. 4 shows the position of the various switches and the energization of the relays of the device of Fig. 2 for the several conditions of operation for producing the several necessary knitting speeds. In the operation of the device of Fig. 2, the slow starting speed of 8 courses per minute is produced by first moving the push button switch 8C to closed circuit position and then moving contact device M to closed circuit position which will energize relay 1 through a circuit which comprises conductor Y of the source of alternating current, conductor 38, contact device M, conductor 48, contact device O, conductor 44, the contacts of limit switch CC, conductor 48, the coil of relay 1 and conductors 50 and 52 to the conductor Z of the source of alternating current. At the same time relays 4 and 5 will be energized to close their contact elements 34 and 38 to place the maximum load upon the generator 38. At this time, relays 2 and 3 will be deenergized, since the contact element 68 of relay 5 will be moved to the open circuit position, and the maximum resistance will be connected in the rotor circuit of the motor 10. Under these conditions, the speed torque characteristic of the motor represented by the curve E of Fig. 5 will be produced and the knitting machine will run at a speed of approximately 8 courses per minute.

To produce the high speed necessary for knitting the welt, the push button switch 8C will be moved to the open circuit position and the push

button switch F will be moved to the closed circuit position. This will energize relay 2 to connect the minimum of resistance in, or short circuit, the rotor circuit of motor 10, to produce the speed torque characteristic of motor 10 represented by curve A of Fig. 5.

When it is necessary to turn the welt, the welt turning speed of 8 courses per minute is produced by the closing of the contact elements 10 of the limit switch W by the protuberances 94 on the belt 100 of the control device 88 which will energize relays 4 and 5 and will cause relay 2 to be deenergized through the opening of the contact element 60 of relay 5. Under these conditions, the maximum of resistance will be connected in the rotor circuit of the motor 10 and the maximum load will be placed upon the motor 10 by connecting the minimum resistance in circuit with the generator 38.

20 After the control device 88 permits the limit switch W to move its contacts to open circuit position, the conditions which existed before the contacts of limit switch W were closed will again be reestablished and the knitting machine 25 will run at its high knitting speed of 60 to 75 courses per minute.

The narrowing speed is automatically produced by the opening of the contact elements of limit switch N by the control device 88 at the proper points in the knitting cycle. It will be seen that when the contact elements of limit switch N are open, relays 2 and 3 will be deenergized and only relay 4 will be energized. This will produce the speed torque characteristic 30 of motor 10 represented by the curve E of Fig. 5, and will produce a knitting speed of approximately 30 courses per minute.

The slow knitting speed may be produced automatically by the limit switch SL controlled 40 by the protuberances 94 on belt 96 of the control device 88 or by moving the switching device F to the open circuit position. It will be noted that the moving of either switching device F to open circuit position or the opening of the 45 contact elements of limit switch SL will open the circuit of relay 2 to close the circuit through relay 3 by moving the contact element 98 of relay 2 to closed circuit position. This operation will cause the contact element 28 of relay 50 3 to close to connect only a part of the resistances 16, 20 and 24 in the rotor circuit of the motor 10 and the speed torque characteristic range produced thereby is represented by the range of speed torque characteristic between the 55 curves B and C of Fig. 5, and will produce knitting speeds of between 40 and 60 courses per minute.

It will be apparent that the amount of resistance connected in the output circuit of the generator 38 may be varied by the movable resistor contact which is connected in circuit by the contact element 38 of relay 5 of the devices of both Figs. 1 and 2, and in this way narrowing speed torque characteristics other than that represented by the curve D of Fig. 5 may be produced just as the variation of the value of resistances 14, 18 and 22 and 16, 20 and 24 may produce different speed torque characteristics within the range bounded by the lines A, B and 70 C.

It is understood that the invention herein disclosed is not limited in its application to a knitting machine but may be applied to any machine where a large range of speeds is necessary while maintaining a substantially constant

5 torque on a driven machine. It will be seen that we have provided a system which may be governed automatically or manually for controlling the speed-torque characteristics of a motor so that a high torque may be maintained on a driven machine while the speed of the machine is varied over a wide range and have provided a control system which will produce the several widely varying speeds necessary for the several steps in the knitting cycle of a full-fledged hosiery knitting machine, while maintaining the necessary torque to drive the machine.

In compliance with the requirements of the patent statutes, we have shown and described herein the preferred embodiments of our invention. It is to be understood, however, that the invention is not limited to the precise constructions shown and described but is capable of modification by one skilled in the art, the embodiments herein being merely illustrative of the principle of our invention.

We claim as our invention:

1. A speed control system for a knitting machine, comprising, an induction motor for driving the machine, and means for causing said motor to run at a relatively low speed while starting the machine while maintaining a relatively high starting torque comprising a series generator driven by said motor and manually controlled means for placing a selectively variable load upon said generator.

2. In combination, a machine which requires a different speed for each of a plurality of operations throughout the knitting cycle, an induction motor for driving said machine, a first speed control means for causing said motor to operate at the lower speeds within the required speed range comprising a series generator driven by said motor and means for varying the load on said generator, a second speed control means for causing said motor to operate at the higher speeds within the required speed range comprising means controlled in accordance with the operation of the knitting machine for varying the resistance of the rotor circuit of the motor, and means for actuating said first and second speed control means in accordance with a predetermined sequence of operation during the knitting cycle.

3. In combination, a machine which requires a plurality of different speeds throughout the knitting cycle, an induction motor for driving said machine, speed control means for causing said motor to operate at the higher speeds within the required speed range comprising means for varying the resistance of the rotor circuit of the motor, speed control means for causing said motor to operate at the lower speeds of the required speed range comprising a generator driven by said motor and means for varying the load on said generator, manually controlled means for actuating said speed control means to produce certain of the required motor speeds and other actuating means for said speed control means controlled by the knitting machine for producing other of the required speeds in a predetermined sequence.

4. A drive system for a machine which requires a wide speed range while maintaining a high torque, comprising, a wound rotor induction motor for driving the machine, means for varying the rotor circuit resistance to vary the motor speed in the upper part of the speed range, and means for varying the load on the motor to vary

the motor speed in the lower part of the speed range, comprising a series generator driven by said motor and means for selectively varying the load on the generator in accordance with the desired motor speed in the lower part of the speed range.

5. A drive system for a variable speed machine, comprising a wound rotor induction motor for driving the machine, means for varying the resistance of the rotor circuit to vary the motor speed in the upper part of the speed range and means for varying the motor speed in the lower part of the speed range, comprising a dynamo-electric machine driven by said motor and means for selectively changing the load on said dynamo-electric machine in accordance with the desired motor speed in the lower part of the speed range.

6. In combination, a hosiery knitting machine, a wound rotor induction motor connected to drive said machine, a plurality of resistance elements, relay means for connecting various ones of said resistance elements in the rotor circuit of said motor, a generator driven by said motor, relay means for connecting various ones of said resistance elements in the output circuit of said generator, manually operative means for selectively energizing certain of said relays to cause said motor to operate at the desired speeds, and means automatically operated in a predetermined sequence by and in accordance with the operation of said knitting machine for selectively energizing certain of said relays to cause said motor to operate at predetermined speeds in a predetermined sequence during the knitting cycle.

35. 7. In combination, a hosiery knitting machine, a wound rotor induction motor connected to drive said machine, a plurality of resistance elements, relay means for connecting various ones of said resistance elements in the rotor circuit of said motor, a generator driven by said motor, relay means for connecting various ones of said resistance elements in the output circuit of said generator, manually operative means for selectively energizing certain of said relays to cause said motor to operate at the desired speeds, and means automatically operated in a predetermined sequence by and in accordance with the operation of said knitting machine for selectively energizing certain of said relays to cause said motor to operate at predetermined speeds in a predetermined sequence during the knitting cycle, and limit switch means for deenergizing said motor at predetermined phases of the knitting cycle.

8. In combination, a hosiery knitting machine, a wound rotor induction motor for driving said machine, a plurality of resistance elements, relay means for connecting various ones of said resistance elements in the rotor circuit of said motor to thereby vary the speed of the motor in the upper part of the desired speed range for the knitting machine, a generator driven by said motor and relay means for connecting various ones of said resistance elements in the output circuit of said generator to thereby vary the speed of said motor in the lower part of the desired speed range for the knitting machine, manual means for selectively energizing said relays to thereby cause said motor to operate at the desired speed, and a plurality of limit switches actuated in a predetermined sequence by and in accordance with the operation of said knitting machine connected with said relays to thereby vary the speed of the motor in a predetermined sequence during the knitting cycle.

75. 9. A drive system for a variable speed ma-

chine, comprising, a wound rotor induction motor for driving the machine, means for varying the resistance of the rotor circuit to vary the motor speed in the upper part of the speed range, and means for selectively varying the motor speed 5 while maintaining a relatively high motor torque in the lower part of the speed range, comprising, a variable auxiliary load for the motor and means for selectively varying said auxiliary load in accordance with the desired speed changes in the 10 lower part of the speed range.

10. A control system for a hosiery knitting machine, comprising, an induction motor for driving the machine, and means for causing said motor to run at a relatively low speed while 15 maintaining a relatively high motor torque while starting the machine comprising manually controlled means for placing an auxiliary load upon said motor, and means for selectively varying said auxiliary load in accordance with the desired motor speed in the lower part of the motor speed range.

11. In combination, a hosiery knitting machine which requires a different speed for each of several operations throughout the knitting cycle, an induction motor for driving said machine, speed-control means for causing said motor to run at the lower speeds within the required speed range comprising an auxiliary loading means for the motor, speed control means for 20 causing said motor to run at the higher speeds within the required speed range comprising means for varying the resistance of the rotor circuit of said motor, and means controlled by the knitting machine for actuating said speed 25 control means in accordance with a predetermined sequence of operation of the knitting machine during the knitting cycle.

12. In combination, a hosiery knitting machine which requires a plurality of different 40 speeds throughout the knitting cycle, an induction motor for driving said machine, speed control means for causing said motor to run at the higher speeds within the required speed range comprising means for varying the resistance of 45 the rotor circuit of the motor, speed control means for causing said motor to run at the lower speeds of the required speed range comprising an auxiliary adjustable loading means for said motor, manually controlled means for actuating 50 said speed control means to produce some of the required motor speeds and other actuating means for said speed control means controlled by the knitting machine for producing other of the required speeds in a predetermined sequence. 55

13. In combination, a knitting machine which requires a plurality of different speeds throughout the knitting cycle, a wound rotor induction motor for driving said machine, speed control means for causing said motor to run at the higher speeds within the required speed range comprising means for inserting various amounts of resistance in the rotor circuit of the motor, speed control means for causing said motor to run at 60 the lower speeds of the required speed range comprising an adjustable auxiliary loading means for said motor, manually controlled means for actuating certain of said speed control means to produce certain of the required speeds, means including a limit switch controlled by the knitting machine for actuating other of said speed control means to produce another of said required speeds at predetermined intervals. 65

14. In combination, a knitting machine which

- requires a plurality of different speeds throughout the knitting cycle, a wound rotor induction motor for driving said machine, speed control means for causing said motor to operate at the higher speeds within the required speed range comprising means for inserting various amounts of resistance in the rotor circuit of the motor, speed control means for causing said motor to run at the lower speeds of the required speed range comprising a generator driven by said mo-

tor and means for varying the load on said generator, manually controlled means for actuating certain of said speed control means to produce certain of the required speeds, means including a limit switch controlled by the knitting machine for actuating other of said speed control means to produce another of said required speeds at predetermined intervals. 5
